DESIGN FOR A SHOE

Saul Litvack, New York, N. Y., assignor to Dronoff Shoe Products Inc., Carlisle, Pa.

Application February 5, 1949, Serial No. 704

Term of patent 3½ years

(Cl. D7—7)

To all whom it may concern:

Be it known that I, Saul Litvack, a citizen of the United States of America, residing in New York, county of New York, and State of New York, have invented a new, original, and ornamental Design for a Shoe, of which the following is a specification, reference being had to the accompanying drawing, forming part thereof.

The figure is a perspective view of a shoe, showing the essential features of my design in full lines, the invention being characterized by the vamp portion thereof. The opposite side presents substantially the same appearance as that shown.

I claim:

The ornamental design for a shoe, substantially as shown and described.

SAUL LITVACK.
